UNITED STATES PATENT OFFICE

CLYTUS C. MILLER, OF MEMPHIS, TENNESSEE

VENDING MACHINE

Application filed December 6, 1928. Serial No. 324,195.

This invention relates to improvements in vending machines and especially to machines of this class in which the operation is initiated by the insertion of a coin. It has especially relation to a machine for vending a number of articles of one kind, such for instance, as ordinary pencil tablets or flat boxes containing packaged articles.

The objects of this invention are:

- 10 (a) To provide a vending machine in which the vending operation having been initiated by the insertion of a coin will thereafter automatically be completed by the machine itself;
- 15 (b) To provide a vending machine for handling a large number of similar articles in which the weight of the articles or at least a large proportion of them will be prevented from resting on and thereby impeding the 20 operation of delivery of the particular one of the articles which is being vended;
- 25 (c) To provide means in a vending machine for utilizing the weight of a number of superimposed articles to assist in the operation of the machine;
- 30 (d) To provide means for diverting imperfect coins or slugs so that the machine will not be operated by them;
- 35 (e) To provide means for closing the coin slot when the machine is empty and thereby prevent coin insertion at such time; and
- 40 (f) To generally improve the design and construction of such a machine.

The means by which the foregoing and other objects are accomplished and the method of their accomplishment will readily be understood from the following specification on reference to the accompanying drawings, in which:

- 45 Fig. 1 is a front elevation of the machine.
- Fig. 2 is a rear elevation.
- Fig. 3 is a side elevation on approximately twice the scale of Figs. 1 and 2 showing the lower portion only of the machine.
- 45 Fig. 4 is a sectional plan taken on the line IV—IV of Fig. 3, with the machine empty.
- Fig. 5 is a sectional elevation taken on the line V—V of Figs. 1 and 4, looking in the direction of the arrow showing the lower portion only of the device.

Fig. 6 is a similar sectional elevation taken on the line VI—VI of Figs. 2 and 4.

Fig. 7 is a sectional rear elevation taken on the line VII—VII of Fig. 3, showing operating and governing mechanism.

Figs. 8 and 9 are respectively fragmentary front and side elevations of a portion of the machine showing the coin slot closure mechanism.

Referring now to the drawings, in which the various parts are indicated by numerals, the machine comprises a base 10 from which four side members 11 extend vertically upward forming the frame of the machine. The upper ends of these side members are connected together by a top 12.

Secured to the frame members 11 near the top and bottom ends thereof are brackets 13 in which are journaled two top shafts 14 and two bottom shafts 15. Mounted on each of the top shafts and on each of the bottom shafts are pairs of sprocket wheels 16, 17 respectively, each sprocket 17 being vertically below and in alignment with a top sprocket 16. 18 are sprocket chains each disposed on a top sprocket 16 and bottom sprocket 17, and secured to and connecting the pair of chains on each side of the machine are shelves 19 preferably made of very light angle iron.

Each of the shafts 15 extends rearwardly beyond the rear bearing 13 and is journaled in an additional bearing 20 beyond which bearing it projects. Mounted on and secured to the end of the shafts 15 are gears 21, which gears mesh with and are driven by pinions 22, these pinions 22 are mounted on and secured to shafts 23, which shafts are journaled in suitable bearings projecting from the base 10. 24 are bevel pinions mounted on and secured to the opposite ends of the shafts 23, which pinions mesh with and are driven by bevel pinions 25, which latter pinions are both mounted on and secured to a transverse shaft 26, journaled in suitable bearings in the base, thus synchronizing rotation of the shafts 15.

Also mounted on and secured to the shaft 26 is a sprocket pinion 27, which is driven by a sprocket gear 28 through a sprocket chain

29, this chain also passes around an idler 30 and drives a sprocket pinion 31, which is secured on a transverse shaft 32.

The driving gear 28 is mounted on and secured to a transverse power shaft 33 which shaft passes through a casing 34 in which is enclosed a typical form of coil spring driving mechanism, which mechanism being of any usual type, need not be illustrated. 35 10 is a worm gear mounted on and secured to the shaft 33 which gear meshes with a worm 36 secured on a shaft 37. The end of the shaft 37 is square so that a crank may be placed thereon for the purpose of winding 15 the driving spring.

Mounted on the shaft 26, which is driven by the pinion 25 are two sprocket gears 38. 39 is an idler shaft parallel to the shaft 26 on which shaft sprocket gears 40 preferably 20 identical in size with the gear 38 are mounted. 41 are vending sprocket chains, each of which chains is disposed around a sprocket 38 and a sprocket 40 and carries four delivery dogs 42.

25 Mounted on and secured to the shaft 32 are gears 43, 44 and a cam 45. The gear 43 meshes with a pinion 46 which is mounted on and secured to a shaft 47 on which in turn is secured a gear 48, which gear meshes 30 with a pinion 49 secured on a shaft 50. Secured on the shaft 50 is a gear 51 which meshes with a gear 52 mounted on a shaft 53. The gear 52 meshes with a pinion 54 which is secured on a shaft 55 on which shaft 35 is mounted a governor 56, the gears 43—45, 48—49, 51—52—54 establish a train of gearing between the shaft 32 and the governor 56 whereby high rotational speed of the governor will be secured from the low speed 40 shaft 32. Meshing with the gear 44 is a pinion 57 which is mounted on a shaft 58 which shaft also carries a cam 59 which cam actuates a counter 60, through the intermediary of the rocker arms 61, 62, connecting rod 45 63, and the arm 64. The counter which is for the purpose of recording the number of articles vended being of some usual or desired make purchased in the open market, need not be here illustrated.

50 The cam 45 is furnished with oppositely disposed pockets 65 which pockets are in turn engaged by a roller 66 carried on one end of a rocker arm 67, the roller 66 being adapted to drop into each of the pockets 65 in succession and thereby to check or limit the movement of the cam 45 to half a turn. The rocker arm 67 is secured to a shaft 68 which passes through and is journalled in 55 the frame member 69. This frame member and a frame member 70 also form bearings for the shafts 32, 47, 50, 53 and 55. Secured to the shaft 68 is a second rocker arm 71, which arm carries a roller 72 which rests 60 against a trip cam 73, which cam is pivotally

supported by a pin 74 projecting from the frame member 69.

Integral with the cam 73, and disposed oppositely thereto with relation to the pin 74, is a trigger 75 adapted to be depressed 70 by a coin 76 dropping thereon.

Mounted on the governor shaft is a disc 77 which is shifted to the left in Fig. 7 against oppositely disposed brake pads 78 as the governor speeds up. These brake pads are carried by arms 79 pivotally mounted which may be shifted to adjust the brake tension by the thumb-nut 80. Also mounted on the governor shaft is a disc 115, above which an arcuate brake shoe 116 is 80 carried by a flexible arm 117. The arm 117 is depressed by the cam 59 and applies a brake directly to the governor to positively stop the same. This stopping action is so timed that the cam releases the governor again as the roller 66 seats in the cam notch 65.

81 are parallel rails extending from front to rear of the base 10 and lying alongside and parallel to the chains 41 on which rails the article to be vended, rests. 82 are vertical stop plates attached to the rear of the rear frame members 11 and extending upward therewith substantially their entire height. 83 are similar stop plates attached 95 to the front frame members 11, these latter stop plates however are provided with slots 84 through which are disposed pins 85 so that they may be laterally shifted in charging the machine. It will be understood that where the machine is enclosed in a cabinet as it should be, these stop plates are dispensed with and their function assumed by the cabinet.

86 are articles such as writing tablets disposed on the shelves 19. It will be particularly noted that each pair of shelves supports a number of these tablets and prevents the weight thereof from being transmitted to the tablets therebelow and that likewise 105 additional tablets thereabove are supported in groups by the shelves. Preferably the distances between shelves is so arranged that a dozen of the articles to be vended may be carried by each pair of shelves.

87 is a coin slot from which a coin chute 88 leads rearwardly and downwardly. 89 is a swinging chute pivotally supported at 90 and counterbalanced by an adjustably mounted weight 91, and disposed above this chute is a horseshoe magnet 92. Leading from the end of the swinging chute 89 when in raised position is a slug chute 93 and disposed immediately below this is an operating chute 94. Each of these chutes terminates in a vertically disposed chute 95, 96 respectively. The chute 95 which leads from the slug chute 93 is provided with a deflecting portion 97 through which diverted slugs pass to a receptacle 98. The chute 125 130

96 leads directly toward the trigger 75. The swinging chute 89 is so balanced that it will depress with the weight of the particular coin which is to be inserted to operate the machine, any lighter coin will fail to depress the chute and therefore be diverted through the slug chute into the receptacle for slugs. Any iron slug even of the proper weight will be held up by the magnet and such slug likewise be diverted to the slug receptacle. It will be especially noted that any slug which is diverted will not be returned to the person attempting to defraud the machine and that therefore in any one neighborhood or especially in schools where vending machines are installed, the supply of slugs will diminish and the loser thereof will spread the news, thus deterring others from such attempts.

In order to prevent the attempted operation of the machine when the same is empty, or as I prefer to make it, when there is only one tablet left therein, I provide a slot closing plate 99 having inclined slots 100 therein, through which latter slots pins 101 are passed. This plate when pulled downward will also shift laterally and close the coin slot 87. Secured to and depending from this plate is a rod 102 the lower end of which is carried by a crank arm 103, which is oscillatably mounted in a bracket 104. Secured to the rod 102, is a bracket 105 having a boss 106, through which a rod 107 is slidably disposed. 108 is a thumb-nut limiting downward movement of this rod and providing for adjustment of the length thereof. 109 is a bell crank lever with the horizontal arm of which lever the lower end of the rod 107 is connected. 110 is a tension spring pulling this arm downward. The bell crank lever 109 is mounted on a pin 111 projecting forwardly from the frame member 11 and has a vertical portion which extends downward and engages against the articles which are being vended. When these articles drop below the end of this vertical arm the spring 110 acting downward causes the plate 99 to move downwardly and laterally and thereby closes the coin slot.

The crank arm 103 is carried by a rod 112 which is oscillatably mounted in the bracket 104, and to this arm a flap 114 is secured, the opposite end of this flap being similarly mounted. This flap is swung outward each time an article is vended and depresses the rod 102 when so swung thus independently closing the coin slot and preventing operation of the machine until the article is entirely removed.

It will be noted that the weight of the articles to be vended resting on the shelves 19 urges these shelves downward and, through the chains which carry the shelves, this action is transferred to the shafts 15,

thence through the gears 21 pinions 22 and bevel gears 24, 25, to the shaft 26 which is driven by the spring motor so that the weight of the articles being vended is utilized in assisting the action of the motor.

The downward travel of the shelves must be regulated to coordinate with the number of deliveries made by the chain, and the thickness of the article delivered.

It will be noted from Fig. 6, that the diameter of the sprocket 38 is such that one-half turn of this sprocket is necessary in order to advance the upper lug 42 to the position now occupied by the next forward lug, which movement constitutes one delivery cycle. The sprocket 38 is mounted on the shaft 26 and this shaft, through the bevel gears 24—25, the pinions 21 and the gears 22, transfers the movement to the downwardly moving shelves. Preferably the gears 24 and 25 are of equal size, the relation therefore of the pinions 21 and the gears 22, together with the diameter of the sprockets 17 must be such that one-half revolution of the pinion 38 gives exactly a downward movement equal to the space between two shelves divided by the number of articles thereon. In the present case the shelves are two and one-half inches apart and each shelf is designed to accommodate 12 articles. Each of the sprockets 17 has eight teeth of one-half inch pitch, so that each revolution of the sprocket moves the shelves down four inches, thus 5/96 of a revolution is required. The relation of the half revolution pinion 21 to the gear 22 is 10 to 96 which accomplishes the ratio.

It will be understood that for a different number of articles filling the shelves the ratios of the pinions 21 and gears 22 will necessarily be correspondingly varied.

In using the machine the front guards are shifted and one dozen tablets are placed on each pair of shelves 19 until the machine is filled or such number as may be desired placed therein. The spring motor is then wound up by means of the shaft 37 and the machine is ready for use. A coin dropped in the coin slot 87 passes through the coin chute 88 into the swinging chute 89, whence, if it is too light or of magnetic material, it passes into the slug chute 93 without operating the machine. If the coin is of proper weight it depresses the chute 89 and passes thence into the chute 94 thence into the chute 96 and on to trigger 75, depressing the latter and causing the tripping cam 73 to shift the lower end of the arm laterally, this movement shifts the upper end of the arm 67, disengaging the roller stop 66 from the cam 45 and permitting the spring motor through the train of gearing shown, to rotate the cam one-half turn. If the speed of rotation should build up too fast, the governor will act through the brake pads to reg-

ulate the speed. The accompanying movement of the vending chains and lugs moves the particular tablet being vended, as shown in Fig. 6, forward from the position A to the dotted position B, displacing the flap 114, in so doing, and this tablet is then in position to be pulled out by the purchaser. While a tablet is thus projecting, and the flap displaced the rod 102 is held in depressed position and the coin slot closed.

As each notch 65 in the cam approaches the roller 66 by which it is to be locked, the counter cam 59 forces the clutch brake 116 against the disc 115 on the governor shaft and thereby arrests the rotation of the governor. This clutching action is so synchronized with the engagement of the stop roller and the cam notch that the slight forward movement accomplished in the final seating of the roller in the notch also disengages the brake clutch from the governor clutch disc leaving the governor free to rotate at the beginning of the next vending movement.

It will be understood that this machine will probably be enclosed in a cabinet and that as a matter of fact a number of these machines may be assembled side by side in cabinets but these cabinets would not constitute any real part of this invention and they are therefore not shown.

It will further be understood that various modifications may be made in this device without departing from the spirit of this invention and I do not wish therefore to be limited to the specific detail herein shown except as the same may be hereinafter specifically set out in the claims.

Having described my invention, what I claim is:

1. In a power operated apparatus having coin actuated means for initiating operation, a vending machine including a pair of parallel horizontally disposed rails, which are adapted to support articles to be vended, means for disposing articles thereon, a pair of shafts extending from rail to rail and substantially at right angles thereto, aligned pairs of sprocket wheels carried by said shafts, and lying slightly below said rails, chains each carried by a pair of said sprocket wheels, four lugs equally spaced, carried by each of said chains and adapted to be advanced thereby in progressive cycles, into, along, and out of, the path of an article on said rails, and means for effectuating and controlling said advancement, comprising a motor, gearing connecting said motor and one of said sprocket shafts, a cam shaft, a cam secured thereon, said cam having a pair of pockets oppositely disposed on the periphery thereof, a detent adapted to engage said pockets successively, means for releasing said detent from one of said pockets, and for engaging same with a succeeding pocket, gearing connecting, and synchronizing movement of, said cam and said chains, whereby release of said detent from one of said pockets and engagement with the second thereof will permit a cycle of movement of said chain lugs, a governor, gearing connecting said governor and said cam shaft and driving said governor at an increased speed over said cam shaft, a disk on said governor shaft, a brake shoe adapted to engage against said disk, a rotatable member adapted to force said shoe against said disk, and gears driving said member from and timing same with, said cam shaft whereby said member will force said shoe against said disk as said cam pockets approach said detent therefor, and release same as said detent seats in said pocket.

2. In a power operated apparatus having coin actuated means for initiating operation, a vending machine including a pair of parallel horizontally disposed rails, which are adapted to support articles to be vended, means for disposing articles thereon, a pair of shafts extending from rail to rail and substantially at right angles thereto, aligned pairs of sprocket wheels carried by said shafts, and lying slightly below said rails, chains each carried by a pair of said sprocket wheels, four lugs equally spaced, carried by each of said chains and adapted to be advanced thereby in progressive cycles, into, along, and out of, the path of an article on said rails, and means for effectuating and controlling said movement comprising a motor, gearing connecting said motor and one of said sprocket shafts, a cam shaft, a cam secured thereon, said cam having a pair of pockets oppositely disposed on the periphery thereof, a detent adapted to engage said pockets successively, means for releasing said detent from one of said pockets, and for engaging same with a succeeding pocket, gearing connecting, and synchronizing movement of, said cam and said chains, whereby release of said detent from one of said pockets and engagement with the second thereof will permit a cycle of movement of said chain lugs, a governor, gearing connecting said governor and said cam shaft and driving said governor at an increased speed over said cam shaft, a disk on said governor shaft, a brake shoe adapted to engage against said disk, a rotatable member adapted to force said shoe against said disk, and gears driving said member from and timing same with, said cam shaft whereby said member will force said shoe against said disk as said cam pockets approach said detent therefor, and release same as said detent seats in said pocket.

3. In a power operated apparatus having coin actuated means for initiating operation, a vending machine including a pair of parallel horizontally disposed rails, 85

which are adapted to support articles to be vended, means for disposing articles thereon, a pair of shafts extending from rail to rail and substantially at right angles thereto, aligned pairs of sprocket wheels carried by said shafts, and lying slightly below said rails, chains each carried by a pair of said sprocket wheels, lugs equally spaced, carried by said chains and adapted to be advanced thereby in progressive cycles, into, along, and out of, the path of an article on said rails, and means for effectuating and controlling said advancement, comprising a motor, gearing connecting said motor and one of said sprocket shafts, a cam shaft, a cam secured thereon, said cam having pockets equally spaced around the periphery thereof, a detent adapted to engage said pockets successively, means for releasing said detent from one of said pockets, and for engaging same with a succeeding pocket, gearing connecting, and synchronizing movement of, said cam and said chains, whereby release of said detent from one of said pockets and engagement with a second thereof will permit a cycle of movement of said chain lugs and force an article placed on said rails into delivered position.

4. In a power operated apparatus having coin actuated means for initiating operation, a vending machine including a pair of parallel horizontally disposed rails, which are adapted to support articles to be vended, means for disposing articles thereon, a shaft extending from rail to rail and substantially at right angles thereto, means actuatable by said shaft adapted to be advanced thereby into, along, and out of the path of an article on said rails, and to be retracted by said shaft into position for additional advancement, and means for effectuating and controlling said advancement comprising a motor, gearing connecting said motor and said shaft, a cam shaft, a cam secured thereon, said cam having pockets equally spaced around the periphery thereof, a detent adapted to engage said pockets successively, means for releasing said detent from one of said pockets, and for engaging same with a succeeding pocket, gearing connecting, and synchronizing movement of, said cam and said shaft, whereby release of said detent from one of said pockets and engagement with a second thereof will permit a cycle of movement of said actuating means, a governor, gearing connecting said governor and said cam shaft and driving said governor at an increased speed over said cam shaft, a disk on said governor shaft, a brake shoe adapted to engage against said disk, a rotatable member adapted to force said shoe against said disk, and gears driving said member from, and timing same with, said cam shaft whereby said member will force said shoe against said disk as said cam

pockets approach said detent therefor, and release same as said detent seats in said pocket.

5. In a power operated apparatus having coin actuated means for initiating operation, a vending machine including a pair of parallel horizontally disposed rails, which are adapted to support articles to be vended, means for disposing articles thereon, a shaft extending from rail to rail and substantially at right angles thereto, means actuatable by said shaft adapted to be advanced thereby into, along, and out of the path of an article on said rails, and to be retracted by said shaft into position for additional advancement, and means for effectuating and controlling said advancement comprising a motor, gearing connecting said motor and said shaft, a cam shaft, a cam secured thereon, said cam having pockets equally spaced around the periphery thereof, a detent adapted to engage said pockets successively, means for releasing said detent from one of said pockets, and for engaging same with a succeeding pocket, gearing connecting, and synchronizing movement of, said cam and said shaft, whereby release of said detent from one of said pockets and engagement with a second thereof will permit a cycle of movement of said actuating means, and force an article disposed on said rails into delivered position.

In testimony whereof I hereunto affix my signature.
